THEODORE KARDONG, OF MINNEAPOLIS, MINNESOTA.

SPACING BAR FOR USE IN REENFORCED-CONCRETE COLUMNS.

1,409,217.

Specification of Letters Patent.

Patented Mar. 14, 1922.

Application filed January 31, 1920. Serial No. 355,375.

To all whom it may concern:

Be it known that I, THEODORE KARDONG, a citizen of the United States, residing at Minneapolis, in the county of Hennepin and

5 State of Minnesota, have invented a new and useful Spacing Bar for Use in Reinforced-Concrete Columns, of which the following is a specification.

This invention has reference to spacing bars for use in connection with reinforced concrete columns, and its object is to provide a one-piece structure which will effectively hold the turns of coils used in the manufacture of concrete columns in properly spaced 15 relation, grouping the terminal turns together and spacing the intermediate turns, with the spacers of a character permitting them to be readily stamped from strips of metal and then easily applied and clamped 20 in place against liability of displacement.

A spacing bar constructed in accordance with the invention comprises an elongated metallic strip with blank ends and intermediate bends opposite which latter punched-out tongues are formed so that the elongated plain ends may be bent upon themselves to produce loops enclosing a plurality of turns at the corresponding ends of the coil and the intermediate turns of the coil may be individually seated in the bends of the strip or bar, with the tongues subsequently bent over the individual turns of the coil to lock them in position.

When the coil is engaged by a plurality of 35 such spacer strips, it forms a very rigid cage capable of being embedded in a concrete column so as to thoroughly reinforce the column, and as the coil and strips are intimately locked together displacement cannot occur 40 and the reinforcing action is particularly efficient.

The invention will be best understood from a consideration of the following detailed description taken in connection with 45 the accompanying drawing forming a part of this specification, with the understanding, however, that the invention is not confined to any strict conformity with the showing of the drawing, but may be changed and modified so long as such changes and modifications mark no material departure from the salient features of the invention as expressed in the appended claims:—

In the drawings:—

55 Figure 1 is an elevation, with some parts

in section, showing spacer bars connecting and spacing the turns of a reinforcing coil;

Figure 2 is a section on the line 2—2 of Figure 1;

Figure 3 is an edge view of the spacer bar 60 before being applied to the coil and also showing certain parts in section.

Referring to the drawings, there is shown a coil 1 of suitable conformation for use as a concrete column reinforcement. When 65 embedded in a concrete column, it is of advantage to have the turns of the coil in suitably spaced relation throughout the greater portion of the length of the coil while the terminal turns are brought close 70 together in substantial contact, thus greatly strengthening such part of the column, such closely grouped terminal coils being indicated in Figure 1 at 2, while the individual intermediate coils are indicated at 3. 75

For each reinforcing cage, there is provided a suitable number of spacer bars 4, each comprising a metallic strip of appropriate width and gage with initially straight elongated end portions 5, sufficiently long to 80 be bent upon themselves into substantially closed loops 6, so as to embrace and clamp a plurality of turns 2 of the coil 1.

At appropriate intervals along the length of the spacer bar 4 are punched-out tongues 85 7, each integrally connected at one end with the bar 4 and having the other end free, the tongues initially curving back toward the body of the bar and sufficiently spaced therefrom to permit the introduction of the turns 90 3 between the tongues 7 and the body of the bar 4. Punching out the tongues 7 from the body of the bar 4 leaves elongated recesses or slots 8 and the bar 4, where these slots occur, is bent or indented as shown at 95 9 to constitute seats for the turns 3 and flanking the slots 8.

When the coil 1 has the spacing strips 4 attached to it, the loops 6 at the ends of the strip 4 are made to embrace a plurality of 100 terminal turns, one end portion of the strip embracing a greater number of turns than the other end. In the particular showing of the drawing, one end portion of the strip embraces three turns and the other end two 105 turns, the longer loops 6 alternating in adjacent strips. After the turns 3 are seated in the bends 9, the tongues 7 are returned at their free ends toward the bar 4, thus firmly clamping the turns 3 in the seats 9, with the 110

bars 4 in planes intermediate of the thickness of the turns 3.

The strip 4 with the elongated ends 5, the seats 9 flanking the slots 8, and the tongues 7 formed by the material punched out of the slots 8 but integrally connected with the strips 4, form particularly efficient spacing bars, easily applied to the coils 1, and also easily fastened thereto in a manner rigidly connecting the coils in permanently spaced relation against any possibility, under conditions of use, of the coils spreading or contracting and consequently avoiding all liability of the columns cracking or deteriorating in any way.

The turns 3 enter the seats 9 and the free ends of the tongues are bent into the slots 8, so that the seats 9 and tongues 7 firmly embrace and hold the turns 3 against displacement.

What I claim is:—

1. A reenforcing structure for columns comprising a coil with its intermediate turns longitudinally spaced and its terminal turns 25 in contact, and a spacing strip for engaging each of the turns of the coil to form a reenforcing cage therewith, said strip having its ends formed with embracing loops for a plurality of the terminal turns of the coil.

30 2. A reenforcing structure for columns comprising a coil with its intermediate turns longitudinally spaced and its terminal turns close together, and a spacing strip for engaging each of the turns of the coil to form 35 a reenforcing cage therewith, said strip having its ends elongated and bent back upon themselves to form embracing loops for a plurality of end turns of the coil.

3. A reenforcing structure for columns 40 comprising a coil with its intermediate turns longitudinally spaced and its terminal turns close together, and a spacing strip for engaging each of the turns of the coil to form a reenforcing cage therewith, said strip having 45 its ends elongated and bent back upon themselves to form embracing loops for a plurality of end turns of the coil, the end loops of each strip being of different length

whereby one of the loops embraces more turns of the coil than does the other loop, certain 50 of the strips having their longer loops at one end of the coil and other strips having their longer loops embracing the turns at the other end of the coil.

4. A spacing bar for reenforcing coils for 55 concrete columns, comprising an elongated straight metallic strip, bends provided at regular intervals along said strip and forming curved seats, tongues punched out from the strips and leaving elongated slots where 60 the bends of the strip occur, said tongues being each of a length to partly embrace a turn of the coil with the free end of the tongue entering the slot between the side walls thereof, whereby the coil is seated 65 and locked both by the tongue and by the corresponding bend in the strip.

5. A spacing bar for reenforcing coils for 70 concrete columns comprising an elongated straight strip, a series of elongated slots provided at intervals along said strip, bends provided in the strip where the slots occur, said bends extending out from one side only 75 of the strip, tongues provided on the strip and curved oppositely to the bends in the strip by the portions cut from said slots, the ends of said strip being free from slots and tongues and bent to provide loops of unequal length.

6. A spacing bar for reenforcing coils for 80 concrete columns, comprising an elongated strip with a longitudinal series of tongues punched out therefrom and integral with the strip leaving elongated slots formed by the punching out of the tongue, the strip where 85 the tongues are punched out being bent to form curved seats on opposite sides of the slots to receive turns of the reenforcing coils, and the tongues being each of a length to embrace a respective turn of the coil with 90 the free end of the tongue entering the slot between the side walls thereof.

In testimony that I claim the foregoing as my own, I have hereto affixed my signature.

THEODORE KARDONG.
